UNITED STATES PATENT OFFICE.

MILAN C. BULLOCK AND SAMUEL W. DOUGLASS, OF CHICAGO, ILLINOIS; SAID DOUGLASS ASSIGNOR TO SAID BULLOCK.

MOLD.

SPECIFICATION forming part of Letters Patent No. 501,915, dated July 25, 1893.

Application filed November 26, 1889. Serial No. 331,596. (No model.)

To all whom it may concern:

Be it known that we, MILAN C. BULLOCK and SAMUEL W. DOUGLASS, of Chicago, in the county of Cook and State of Illinois, have invented certain new and useful Improvements in Molds; and we do hereby declare that the following is a full, clear, and exact description thereof, reference being had to the accompanying drawings, and to the letters of reference marked thereon, which form a part of this specification.

This invention relates to molds for casting metal tubular cutter heads for rock core-drills, said heads having cutting diamonds or points located in their annular working faces and held in place by the metal of the head as poured in a molten state about them.

The principal object of the invention is to provide a construction by which a cutter head of this class may be cast in a finished or completed state ready for use without subsequent finishing or manipulation, and in addition to this principal end the invention has the secondary object of providing a mold which is capable of being detached from the casting promptly after the metal forming the same has been poured and set in order that said casting may not break in cooling within the mold, and also that it may be placed in sand as soon as the metal shall have set sufficiently to retain its form, so that in further cooling it may not be excessively chilled.

In the accompanying drawings which illustrate our invention in what we believe to be its best form: Figure 1 is a view in side elevation, of a mold constructed in accordance with our invention. Fig. 2 is a top plan view of the same. Fig. 3 is a vertical, sectional view on the line 3—3 of Fig. 2. Fig. 4 is a vertical, sectional view taken on the line 4—4 of Fig. 2. Fig. 5 is a top plan view of a wedge which is inserted within the core of the mold. Fig. 6 is a view in side elevation of said wedge. Fig. 7 is a central, vertical section, of a contracting core which forms a part of the mold with the wedge piece thereof removed. Fig. 8 is a horizontal, sectional view of the said core on the plane indicated by the line 8—8 of Fig. 7, showing the wedge piece thereof in place. Fig. 9 is a horizontal, sectional view of the mold taken on the line 9—9 of

Fig. 1. Fig. 10 is an enlarged vertical, sectional view of the upper part of the mold, illustrating a modified form of construction embodying our invention, the plane of the section being the same as that indicated by the line 3—3 of Fig. 2. Fig. 11 is a face view of a cutter head such as is cast in the form of mold shown in the foregoing figures. Fig. 12 is an axial section of a cutter head, 6c such as is cast by the mold shown in Figs. 1 to 9 inclusive. Fig. 13 is an axial section of the cutter head, such as is cast by the mold shown in Fig. 10.

Referring to Figs. 1 to 9 inclusive of the drawings, A designates a circular base of the mold, the base being provided at each side with an upright A' which is integral with the base.

A² designates a cylindrical head which is formed integrally with the uprights A' and extending across the space between the said uprights. The base, the uprights and the head together, form the lower part of the mold and are made in two vertical sections, the parting line of which is vertical and is indicated at a, said parting line passing through each of the uprights A' and dividing them about equally, as shown in Figs. 1 and 3. The said sections of the lower part of the mold, lettered respectively a' a² are provided with dowels a¹⁹ (see Fig. 9) to insure the precise registry of the sections when the latter are placed together. To secure said sections of the mold together, hinged horizontal clamp bolts a³ a³ are employed, said bolts being hinged between suitable lugs a⁴ a⁴ upon the lower part of the front section a² and provided on their free screw-threaded ends with nuts a⁵ a⁵. Lugs a⁶ a⁶ are formed upon the rear section a' of the mold and adjacent to the parting line thereof, between which the clamp bolts may swing and against which the nuts on said clamp bolts bear, to hold the sections of the mold rigidly together.

A⁸, Figs. 3, 4 and 9, designates a hinged table or support located between the uprights A' of the mold frame and hinged to the upper part of the rear section a' at a point just below the cylindrical head A² and near the rear of said head, as shown at a⁷. Said hinged table A⁸ is provided at about its center with

a circular opening A^4 which is located centrally under the cylindrical head A^2 , when the said table A^3 is in a horizontal or operative position. The front end of said table is 5 bifurcated, as shown, to form an open slot a^8 , which is located just below the front edge of the cylindrical head A^2 .

A^5 designates a hinged operatively vertical screw-threaded bolt pivoted to the lower side 10 of the head A^2 between the frame uprights A' and provided on its lower end with a nut a^9 . This hinged bolt is adapted to swing into the slot a^8 , so that the nut a^9 thereon may engage the under part of the bifurcation a^8 , and 15 sustain the table in its horizontal position. When the bolt is swung out of the slot a^8 , the table may be lowered upon its hinge-bolt a^7 .

The head A^2 is provided centrally with a circular vertical opening a^{10} , having a diameter equal to the interior diameter of the cutter head which is to be cast in the mold and is formed with a plurality of vertical or spiral grooves a^{17} which serve to prevent the wedge of the mold from turning therein, as 20 hereinafter explained. About midway vertically of the head, the opening a^{10} is enlarged, as seen at a^{11} , to a diameter equal to the exterior diameter of the cutter head to be cast, said enlargement having its side walls vertical and its annular bottom wall horizontal. 25 Said lower wall of the opening a^{11} is provided at intervals with uprising ribs or projections $a^{12} a^{12}$, (seen in Fig. 9 and in dotted lines in Figs. 3 and 4,) which serve to form the waterways or passages for water across the annular face of the cutter head. The sides or vertical walls of the said opening a^{11} are provided with vertical ribs $a^{13} a^{13}$, (Figs. 3, 4 and 9) which serve to form the waterways in the 30 side of the cutter head. The mold has a separate upper part B, having a central opening b^7 and made in two vertically divided sections $B' B^2$, provided with dowel pins $b^9 b^9$ on one member, which enter corresponding holes b^{10} in the other. The upper end of the opening b^7 is flared outwardly as at b^{11} , to facilitate 35 the pouring of the metal into the mold.

The top of the head A^2 is provided with annular inclined and horizontal surfaces, respectively lettered a^{14} and a^{15} , Figs. 3 and 4, which form a seat for the top part B of the mold.

The section B^2 is provided near its parting face b with hinged screw-threaded horizontal bolts $b' b'$, having heads or nuts $b^2 b^2$ and adapted to swing across the parting line into engagement with lugs $b^3 b^3$ on the other section B' , to rigidly hold the sections together. The lower face of the upper part B of the 40 mold has the downwardly and inwardly inclined faces b^4 and b^5 , which conform to the upper inclined and horizontal faces of the head A^2 . An annular, vertical shoulder b^6 between the said inclined and horizontal faces b^4 and b^5 fits within the annular, vertical wall a^{16} of the cylindrical head A^2 and retains the parts in concentric position. The opening b^7

has at its lower end, an enlarged portion b^8 , which is of a diameter equal to the opening a^{11} in the head A^2 , (measuring between the 70 surfaces of the ribs a^{13}) and forms an upward continuation of the said opening a^{11} . The chamber formed by the openings a^{11}, b^7 and b^8 , is the matrix in which the cutter head is cast. The part of the cutter head which is 75 formed within the part b^7 of the matrix is the part which is afterward provided with screw-threads for its attachment to the lower end of the drill tube.

The core of the mold, indicated as a whole 80 by the letter C, comprises, as here shown, a wedge C' and a sleeve or contracting core D, surrounding said wedge. This wedge C' has an enlarged base C^2 and an upright reduced part C^3 , which latter is of the same diameter 85 as the lower part of the opening a^{10} in the head A^2 . The upright C^3 of the wedge is provided with a plurality of vertical or spiral ribs $c c$ which interfit with the grooves a^{17} of the opening a^{10} in the head A^2 , and thus prevent the 90 wedge from being turned within the head. The base of the wedge is larger than said opening a^{10} and rests upon the hinged table A^3 , the wedge being passed upwardly through the said opening a^{10} and the table being then 95 swung up under it and secured in its horizontal position. When the wedge C' is in this position in the mold, the part C^3 thereof extends upwardly, desirably to a point about even with the upper end of the enlargement 100 a^{11} of the opening in the head. The sides of the body of said upright part are or may be vertical, while the ribs $c c$ thereon may also be vertical or they may taper inwardly and upwardly from a point about even with the 105 bottom of the opening a^{11} . When the said wedge is in place, the ribs or projections c thereon are opposite the spaces between the ribs a^{13} , as best shown in Fig. 9, and, as also shown in Fig. 9, the projections or ribs a^{12} in the bottom of the cavity a^{11} are not radially arranged but lead obliquely from one of the ribs a^{13} to an adjacent rib c on the wedge.

For convenience of construction, an annular groove c' is formed in the lower end of the uprising part C^3 of the wedge adjacent to the base C^2 , as shown in Fig. 6, said wedge being preferably cast or forged of cylindric form and the ribs c formed thereon by planing out the metal between them. Above its upright part C^3 , the wedge is again reduced in size at c^2 and presents a shoulder c^3 . From the top of the reduced portion c^2 , the wedge is still further reduced in size and presents an upwardly extending and tapering stem C^4 . An upwardly 115 facing shoulder c^4 is thus formed between the reduced portion c^2 and the stem C^4 , and said shoulder C^4 is provided with an annular groove or depression c^5 surrounding the base of the stem for a purpose to be presently explained. The contracting core D is hollow and its interior is provided with a tapering portion d the walls of which converge upwardly, and which fits around the stem C^4 of

the wedge, a flange d' at the bottom of said tapering portion d to fit into the annular groove c^5 , and a vertical part d^2 closely embraces the reduced portion c^2 of the wedge. 5 The bottom of said contracting core D rests upon the shoulder c^3 of said wedge.

In Figs. 7 and 8, the core D is shown in detail. To adapt said core to be contracted, it is slotted at one side throughout its length, as 10 shown clearly at d^3 in Fig. 8. The slit d^3 is wider at the inner than at the exterior surface of the core, as also shown in Fig. 8, for the purpose of admitting a removable filling piece d^7 . A slot d^4 , extending only part way 15 through the core, is made in the interior of said core about opposite the through slot d^3 to give the requisite flexibility for its contraction. The upper end of the core D is formed with an annular rabbet in its outer 20 margin in which is fitted a ring d^5 , said ring being secured to the core by a cross-pin d^6 , and the object of this ring d^5 being to prevent undue expansion of the core. The 25 wedge-shaped piece d^7 , conforms to the contour of the tapered slot d^3 and has the shape of the core in its outer and inner faces, and when in place presents smooth surfaces continuous with the surfaces of the core.

From the above description, it is manifest 30 that when the wedge piece d^7 is in place in the core and the core is passed down over the stem C^4 , the said stem prevents the wedge-piece from falling out, and the flange d' entering the annular groove c^5 of the wedge 35 C' serves to prevent the expansion of the lower part of said core, while its upper part is held from expansion by the ring d^5 .

The annular space inclosed by the several 40 parts of the mold described, gives a casting which has the appearance in end view indicated by Fig. 11 and in axial section by Fig. 12, e being the external grooves or waterways, formed by the ribs a^{13} , e^2 , the interior grooves or waterways formed by the ribs c and e' 45 grooves or depressions extending across the end face of the casting and formed by the projections a^{12} , and giving communication between said outer and inner waterways, all of said grooves or depressions being thus formed 50 by the several sets of ribs and projections of the mold, wedge and core, as above set forth.

The diamonds are placed in the mold before 55 the metal is poured therein and are embedded in said metal, some of them e^3 being located at the outer and others e^4 at the inner margin of the cutter face between the depression e' , as shown in Figs. 11 and 12. To hold the diamonds in the bottom of the mold and against its outer and inner walls, small metal pins 60 are projected through correspondingly small passages in the metal walls of the mold and are made to bear at their ends against the stones. The holding pins for the inner series of stones are shown at a^{18} , Fig. 4, as passing inward and downward through the mold A^6 65 being thumb screws threaded into the body

of the mold to push the pins A^{18} inwardly endwise. The holding pins for keeping the outer series in place are shown at c^6 , Fig. 3, as passing inward and downward through holes in 70 the wedge C' . These pins are so inclined, as shown, as to hold the stones to the bottom as well as to the sides of the mold and the pins c^6 are accessible for manipulation through the cavity C^5 in the bottom of the wedge C' . 75

The parts described as entering into the mold are put together and operated as follows: First, the two sections a^1 , a^2 of the lower portions of the mold are placed together and secured by the hinged clamp bolts a^3 . The 80 wedge C' is then passed up through the grooved opening a^{10} in the head A^2 , with its ribs fitting the grooves of said opening, and the horizontal table or support A^3 is then lifted to a horizontal position and secured by 85 the bolt A^5 . The outer set of diamonds or cutting points are then inserted in their proper positions and the wires or pins c^6 (which had been previously placed in the wedge but in a retracted position) are forced outwardly by 90 pressure on their upper or outer ends or by means of pliers seizing them in the cavity of said wedge, until they bear against said stones or points. The upper ends of said wires or pins c^6 desirably project a little beyond the 95 outer surface of the wedge so as to be engaged and held in place by the contracting core D which is next applied to the wedge in the position shown in Figs. 3 and 4. The inner set of diamonds or cutting points are next placed 100 in position and the thumb screws A^6 turned to force the pins a^{18} against them. The two sections B' , B^2 of the upper part of the mold are then secured together and placed upon the head A^2 . The mold is now complete. Be- 105

fore pouring the metal into the mold the latter is heated to a proper temperature in a furnace, after which it is placed in an upright position to receive the melted metal. After the metal is poured, and has set the hinged support A^3 is released and allowed to drop, leaving the wedge C' unsupported. A blow struck upon the upper end of the stem C^4 of this wedge drives the latter down through the contracting core and head A^2 , cutting off the pins or 115 wires c^6 and permitting the wedge to be removed through the space between the uprights A' . There being now nothing to interiorly support the wedge shaped filling piece d^7 in the slot of the contracting core D, it may be 120 forced inward by contraction of the core as the latter is compressed by the shrinking of the recently poured metal about it. By removal of the wedge piece, the core D is freed so that it can be lifted or dropped out, and, 125 when this is done the outer parts of the mold are successively parted and the casting released. The casting which will now have been sufficiently set to retain its form will then be taken out and put in sand to cool off slowly 130 and thus avoid excessive chilling of the same. The holding pins or wires a^{18} which pass

through the body A² of the mold being small are broken off when the outer portion of the mold is parted.

The mold above described has several advantages, relating to the facility and the certainty of position with which the diamonds may be placed and retained therein, to accuracy in the form of the casting and to the durability of the cutter head cast in said mold. The first of these advantages constitutes a distinction between the cutter head cast complete, as described, and any other tool provided with cutting diamonds or points heretofore made and with which we are acquainted. So far as we are informed, an integral tubular bit or cutter head has never before been cast complete with the diamonds in it and held in place by the metal as originally poured around them. The former practice has generally been to cast separate pieces or sections with one or a few of the diamonds in them which are to enter into the finished tool, and to set such separate pieces into the metal of the tool, as, for example, in a saw blade. In the present case, the cutter head is integral or formed of a single piece of metal containing all the diamonds or cutting points which it is to carry, supported by the metal as cast about them. The possibility of making the tool thus complete in the first instance is due to the use of the mold or to the mold and the holding wires by which the diamonds are held in place during the process of casting, the walls of the mold and its fixed bottom insuring the positions of the diamonds in a single plane and in concentric circles. Such accuracy in the position of the diamonds is practically of great importance, inasmuch as, if one of several stones excessively projects beyond the proper plane of the cutting face, an excess of work is thrown upon said stone and its cutting edges are soon dulled. The irregularity of its position out of its plane and also the position of a stone outside of its proper circle gives a vibratory motion to the tool in operation which interferes with the accuracy of its work and also with the durability of the tool. When the diamonds are set in separate pieces and affixed to a tool, whether it be a saw blade or a cutter head, this absolute accuracy cannot be attained.

The accuracy in the form of the casting produced by the mold is in itself of material advantage inasmuch as thereby all subsequent finishing of the casting is rendered unnecessary excepting the cutting of a screw thread or the provision of other means thereupon of attaching the head to a drill rod. But such accuracy has direct reference to the durability of the cutter head in use, inasmuch as all filing away of portions of its surface to produce accuracy is obviated. The superficial chill produced by the mold is the same in all portions of its surface, so that it wears with uniformity at all points exposed to the same friction or strain.

The use of a contracting core D provides for the proper shrinking of the casting in its first cooling or setting without fracture of said casting and without the destruction of the core, which may be repeatedly used an indefinite number of times.

In Fig. 10 a modified form of the mold is illustrated having reference to the production of a cutter head the interior opening of which shall contract downwardly to form a chamber for a core-lifting ring and which shall be adapted more especially to receive a thread upon its inner upper surface for the introduction of an externally threaded section of drill tube. This modification presents no departure from the invention already described as being illustrated in Figs. 1 to 9 inclusive.

Fig. 13 illustrates as a vertical, axial section, the form of cutter head which will be produced by a mold constructed in detail as shown in Fig. 10, the lower or working face of the cutter head being in this case the same as produced in the mold as shown in preceding figures and as particularly illustrated in Fig. 11.

In Fig. 10 we have illustrated the head A², as provided with an annular bushing α^{20} forming a removable part of the mold. This construction will be a convenience in manufacture and may be applied to the mold as otherwise illustrated in preceding figures.

It is manifest that the mold above described as being particularly adapted for casting cutter heads for rock drills may be employed for casting other similarly shaped or hollow metal articles and we are therefore not restricted to the use of the mold herein described and claimed for casting such cutter heads alone. We also do not wish to restrict ourselves to the details of construction herein shown, inasmuch as various modifications may be made without departure from our invention, the primary essential of which is that the mold comprises an inner wall or core which is collapsible, and to this end is made in sections.

We claim as our invention—

1. A metal mold, comprising a central member having transverse holes therein to receive holding wires or pins by which to retain diamonds or other separate parts, in proper position within the mold during the pouring; the said central member being provided with a cavity affording access to the holding wires or pins while said member is in position in the mold, substantially as set forth.

2. A sectional metallic mold comprising an external vertically divided body portion forming the external walls of the mold and having an opening through its bottom, a tapered wedge-shaped member projecting upward through said mold, and wholly separate from the mold, a contractible tubular core or sleeve surrounding the tapered member and located wholly separate therefrom within the mold and slit longitudinally at one side and also recessed longitudinally at another side, and

a wholly separate spreader-piece wedge-shaped in cross-section and inserted into the split of the core, substantially as set forth.

3. A sectional metallic mold, comprising an external vertically divided body portion having its two sections hinged together and forming the external walls of the mold and having an opening in its bottom, a tapered member wholly separate from the body portion of the mold and removable downwardly from the mold through the bottom opening thereof, a movable support for the tapered member hinged beneath the body of the mold and having also a central opening, a contractible tubular core or sleeve surrounding the tapered member and located wholly separate therefrom within the mold and split longitudinally at one side and also recessed longitudinally outward at another side, and a wholly separate spreader-piece wedge-shaped in cross-section and inserted into the split of the core, substantially as set forth.

4. A sectional metallic mold, comprising a vertically divided external casing forming the body portion of the mold and having an opening in its bottom, the two portions of the casing being hinged together and having connecting attachments opposite their hinge, a wedge-shaped member wholly separate from the mold and projecting upwardly through the same and also removable downwardly through the bottom of said mold, a contractible tubular core or sleeve surrounding the tapered member and located wholly separate therefrom within the mold and split longitudinally at one side and also recessed outward longitudinally at another side, a separate wedge-piece arranged to enter the longitudinal split of the sleeve a retaining-band

embracing one end of the core or sleeve, and interlocking recesses and projections upon the tapered member and core to prevent expansion of the latter within the mold, substantially as set forth.

5. A sectional metallic mold, comprising a base, a vertical support integral with the base, and a body portion integral with the support, said base, support and body-portion being vertically divided and hinged together, and the internal cavity of the body-portion being of greater diameter at its upper than at its lower portion, a vertically divided top piece for the mold wholly separate therefrom and having an inlet opening communicating with the cavity of the mold, ribs and projections located within the cavity of the mold and serving to form the water-ways of the molded article, a support hinged below the body-portion of the mold and having a central opening, a tapered member wholly separate from the mold and resting upon the support, a longitudinally split and recessed contractible tubular core having external ribs to form the internal water-ways of the molded article, and located within the mold and surrounding the tapered portion, and also wholly separate from the mold and the tapered portion, and a spreader wedge-shaped transversely, inserted into the split of the core, substantially as set forth.

In testimony that we claim the foregoing as our invention we affix our signatures in presence of two witnesses.

MILAN C. BULLOCK.

SAMUEL W. DOUGLASS.
